UNITED STATES PATENT OFFICE

EDGAR W. WARREN, OF GETTYSBURG, PENNSYLVANIA, ASSIGNOR TO J. L. WILLIAMS,
OF GETTYSBURG, PENNSYLVANIA

AERIAL

Application filed October 7, 1930. Serial No. 487,061.

This invention relates to aerials for radio receiving sets, and has for one of its objects to provide an aerial which shall be adapted to increase the range and the selectivity of any receiving set, and which shall be adapted to reduce static interference to the minimum.

The invention has for a further object to provide an aerial of the character stated which shall be simple and compact, which shall be adapted to be readily manufactured at a low cost and which shall be adapted to be easily erected without the aid of a mechanician.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a sectional view taken on a plane extending vertically and centrally through the aerial;

Figure 2 is a sectional view taken on the horizontal plane indicated by the line 2—2 of Figure 1;

Figure 3 is a sectional view taken on the vertical plane indicated by the line 3—3 of Figure 1;

Figure 4 is a sectional view taken on the horizontal plane indicated by the line 4—4 of Figure 1, and

Figure 5 is a sectional view taken on the horizontal plane indicated by the line 5—5 of Figure 1.

The aerial comprises a tube 1 which may be made of copper or of any other suitable metal and may be corrugated longitudinally to add strength and rigidity thereto. The

tube 1 is adapted to be supported in upright position from a roof, pole or the like, and is closed at its upper end by a conical cap 2 and at a point above its lower end by a plug 3.

The cap 2, which is made of metal similar to that from which the tube 1 is made, surrounds and rests upon the upper end of the tube, and the contacting portions of these parts are soldered together, as at 4, to establish a water-proof connection between the same. The plug 3 is arranged within the

tube 1, and is secured in place by screws 5 which pass through the tube and enter the plug. The plug 3 has a snug contact with the inner surface of the tube 1, and any suitable sealing material 6 is arranged between the contacting surfaces of these parts so as to establish a water-proof connection between the same. The connection between the heads of the screws 5 and the tube 1 is rendered water-proof by solder 7 which is applied to the heads and adjacent portions of the tube. The cap 2 and plug 3 provide the tube 1 with a water-proof chamber which extends throughout the greater length thereof.

The plug 3 comprises a lower member 8, an upper member 9 and an intermediate member 10. The plug members 8 and 9 may be made of wood, bakelite or the like, and the plug member 10 may be made of glass or the like. The plug members 8 and 9 have a snug fit with the inner surface of the tube 1, and the plug member 10 is smaller diametrically than the plug members 8 and 9, so as to provide the plug with an annular space 11 which is arranged between the plug members 8 and 9 to prevent any possibility of moisture finding its way along the plug into the chamber of the tube 1.

The plug 3 is provided at its upper side with metallic clips 12 for the reception of a fixed crystal 13 of the conducting and rectifying type. A coil 14 of copper or wire is arranged within the tube 1 between the cap 2 and plug 3, and has its upper end soldered, as at 15, to the apex of the cap 2, and has its lower end soldered, as at 16, to one of the clips 12. A binding post 17 extends through a side of the tube 1 at a point above the plug 3, and is adapted to have the leading-in wire of the receiving set connected thereto. The binding post 17, which is insulated, as at 18, from the tube 1, is connected to the other of the clips 12 by a lead 19 provided with an insulating jacket.

Supporting means for the aerial comprises a standard 20 which is screw threadedly engaged at its upper end with a socket member 21 secured by screws 22 to the lower side of the plug 3. The plug 3 and screws 22 are insulated from the socket member 21, as at

23. The standard 20 is screw threadedly engaged at its lower end with a socket member 24 which is pivotally connected by a bolt 25 to an attaching bracket 26. The socket member 24 and attaching bracket 26 are provided with ears 27 and 28 for the reception of the pivot bolt 25. The attaching bracket 26 may be arranged at any angle to the standard 20 necessary to permit it to be secured by screws 29 to a horizontal or inclined support, as for instance, the roof 30 of a house or other building. After the attaching bracket 26 has been secured in place, the nut of the bolt 25 is tightened to hold the aerial and standard 20 against rocking movement with respect to the attaching bracket.

10 Pins 31 extend inwardly from the tube 1 adjacent the lower end thereof, and arranged within the tube in contact with the lower 20 sides of the pins is a disc 32 of bakelite or other suitable insulating material. The disc 31 is secured in place by clips 33 fixed to the tube 1 and contacting with the lower side of the disc. The disc closes the lower end of 25 the tube 1, and is provided with an opening for the reception of the standard 20.

15 A copper wire is threaded through openings in the upper end of the tube 1 to provide attaching loops 34 arranged at the outer 30 side of the tube, and the openings are sealed by solder, as at 35, to prevent the passage of moisture therethrough. Guy wires 36, preferably of copper, are looped about and soldered to the loops 34, as at 37, and are provided at their lower ends with insulators 38. The guy wires 36 are electrically connected to the tube 1 and coil 14 and constitute a part of the aerial and they may be shortened or lengthened when it is desired to increase 40 or decrease the effective length of the aerial. The guy wires 39 are secured to the insulators 38 and to the roof 30.

45 From the foregoing description, taken in connection with the accompanying drawing, it should be apparent that the tube 1, coil 14 and crystal rectifier 13 are connected in series and that these parts are effectively held against short circuiting contact and fully protected from adverse weather conditions. 50 It will also be understood that the aerial is simple and highly efficient, and that the support therefor permits it to be readily and rigidly attached to a roof or the like.

55 While I have described the principle of the invention, together with the structure which I now consider the preferred embodiment thereof, it is to be understood that the structure shown is merely illustrative and that such changes may be made, when desired, as fall within the scope of the invention as claimed.

I claim:—

1. An aerial comprising in combination a metal tube, a metal closure for the upper end of the tube, an insulating plug within

the tube below its upper end, a crystal rectifier carried by the upper side of the plug, a metal coil within the tube between the closure and plug and fixed at its upper end to the cap and at its lower end to the crystal rectifier, a binding post fixed to and insulated from the tube, and a conductor extending from the binding post to the crystal rectifier. 70

2. An aerial comprising in combination a metal tube, a metal closure sealed to the upper end of the tube, an insulating plug sealed within the tube below its upper end, a crystal rectifier carried by the upper end of the plug, a metal coil within the tube between the closure and plug and fixed at its upper end to the closure and at its lower end to the crystal rectifier, a binding post fixed to and insulated from the tube, and a conductor extending from the binding post to the crystal rectifier. 75

80 3. An aerial comprising in combination a metal tube, a metal closure for the upper end of the tube, an insulating plug within the tube below its upper end, a crystal rectifier carried by the upper side of the plug, a metal coil within the tube between the closure and plug and fixed at its upper end to the cap and at its lower end to the crystal rectifier, a binding post fixed to and insulated 85 from the tube, and a conductor extending from the binding post to the crystal rectifier. 90

95 4. An aerial comprising in combination a metal tube, a metal closure sealed to the upper end of the tube, insulating members arranged in relatively spaced relation and sealed within the tube below its upper end, an insulating member arranged between said first insulating members and smaller than the same to provide a passage between said first insulating members, a crystal rectifier carried by the upper side of the uppermost insulating member, a metal coil within the tube between the closure and said uppermost insulating member and fixed at its upper end to the closure and at its lower end to the crystal rectifier, a binding post fixed to and insulated from the tube, and a conductor extending from the binding post to the crystal rectifier. 100

105 5. An aerial comprising in combination a metal tube having a sealed compartment, a crystal rectifier arranged within said compartment and insulated from the tube, a metal coil within said compartment and connected at one end of the tube and at the other end to the crystal rectifier, a binding post fixed to and insulated from the tube, and a conductor extending from the binding post to the crystal rectifier. 110

115 6. An aerial comprising in combination a metal tube having a sealed chamber, attaching loops passing through and sealed to the tube, guy wires secured at certain of their 120

125

130

ends to the attaching loops, insulators secured to the other ends of the guy wires, a crystal rectifier arranged within the chamber and insulated from the tube, a metal coil 5 within the chamber and connected at one end to the tube and at its other end to the crystal rectifier, a binding post fixed to and insulated from the tube, and a conductor extending from the binding post to the crystal 10 rectifier.

7. An aerial comprising in combination a metal tube, a metal closure for the upper end of the tube, an insulating plug within the tube below its upper end, a crystal rectifier 15 carried by the upper side of the plug, a metal coil within the tube between the cap and plug and fixed at its upper end to the cap and at its lower end to the crystal rectifier, a binding post fixed to and insulated from 20 the tube, a conductor extending from the binding post to the crystal rectifier, a supporting member, and means secured to the plug and detachably engaged with the supporting member.

25 8. An aerial comprising in combination a metal tube, a metal closure for the upper end of the tube, an insulating plug within the tube below its upper end, a crystal rectifier carried by the upper side of the plug, 30 a metal coil within the tube between the cap and plug and fixed at its upper end to the cap and at its lower end to the crystal rectifier, a binding post fixed to and insulated from the tube, a conductor extending from 35 the binding post to the crystal rectifier, a supporting member, means secured to the plug and detachably engaged with the supporting member, and an attaching plate adjustably secured to the supporting member.

40 9. An aerial comprising a metal tube, a metal closure for the upper end of the tube, an insulating plug within the tube below its upper end, a crystal rectifier carried by the upper side of the plug, a metal coil within 45 the tube between the cap and plug and fixed at its upper end to the cap and at its lower end to the crystal rectifier, a binding post fixed to and insulated from the tube, a conductor extending from the binding post to 50 the crystal rectifier, a supporting member, means secured to the plug and detachably engaged with the supporting member, and an insulating member extending across the 55 lower end of the tube and secured to the tube and provided with an opening for the passage of the supporting member.

In testimony whereof I hereunto affix my signature.
